[57] **CLAIM**

The ornamental design for a hanger, as shown and described.

DESCRIPTION

FIG. 1 is a perspective view of a hanger showing my new design;

FIG. 2 is a front elevation view thereof;

FIG. 3 is a top plan view thereof;

FIG. 4 is a rear elevation view thereof;

FIG. 5 is a bottom plan view thereof;

FIG. 6 is a right side elevation view thereof;

FIG. 7 is a left side elevation view thereof;

FIG. 8 is a perspective view of an alternate embodiment of FIG. 1;

FIG. 9 is a perspective view of an alternate embodiment of FIG. 1; and,

FIG. 10 is a perspective view of an alternate embodiment of FIG. 1.

The alternate embodiments are identical to the first embodiment except for the hook portion.
